UNITED STATES PATENT OFFICE.

ARTHUR J. MORGAN, OF CHICAGO, ILLINOIS, ASSIGNOR TO NATIONAL X-RAY
REFLECTOR COMPANY, OF CHICAGO, ILLINOIS.

DESIGN FOR A REFLECTOR.

No. 38,578.

Specification for Design.

Patented May 21, 1907.

Application filed January 11, 1907. Serial No. 351,902. Term of patent 7 years.

To all whom it may concern:

Be it known that I, ARTHUR J. MORGAN, a citizen of the United States, residing at Chicago, in the county of Cook and State of Illinois, have invented a new, original, and ornamental Design for Reflectors, of which the following is a specification, reference being had to the accompanying drawing, forming part thereof, in which—

Figure 1 is a side elevation of the reflector;

Fig. 2 is a rear elevation of the reflector. Fig. 3 is a perspective view looking toward the inside of the reflector.

I claim as my invention

The ornamental design for a reflector shown in the accompanying drawing.

ARTHUR J. MORGAN.
